DESIGN FOR A CANDLEHOLDER

Edward S. Cornell, Jr., Stamford, Conn.

Application May 13, 1944, Serial No. 113,573

Term of patent 14 years

(Cl. D48—2)

To all whom it may concern:

Be it known that I, Edward S. Cornell, Jr., a citizen of the United States of America, residing at Stamford, Fairfield County, State of Connecticut, have invented a new, original, and ornamental Design for Candleholder, preferably of plastic, of which the following is a specification, reference being had to the accompanying drawing, forming part thereof.

In the drawing:

Fig. 1 is a side elevation of a candleholder showing my new design;

Fig. 2 is a top plan view of the candleholder shown in Fig. 1; and

Fig. 3 is a bottom plan view of the candleholder shown in Fig. 1.

I claim:

The ornamental design for a candleholder, substantially as shown.

EDWARD S. CORNELL, JR.
